SOUND DIFFUSING SPEAKER BAFFLE

Aston L. Moore, 220 Hammond Place,
South Bend, Ind. 46601

Filed Dec. 4, 1967, Ser. No. 9,631

Term of patent 14 years

(Cl. D26—14)

FIGURE 1 is a top perspective view of a sound diffusing speaker baffle, showing my new design;

FIGURE 2 is a bottom plan view thereof; and

FIGURE 3 is a sectional view thereof taken along the line III-III in FIGURE 2.

I claim:

The ornamental design for a sound diffusing speaker baffle, as shown.
